UNITED STATES PATENT OFFICE.

NICHOLAS P. LEHR, OF FREMONT, OHIO.

CLOD-CRUSHER AND PACKER.

1,328,171.

Specification of Letters Patent. Patented Jan. 13, 1920.

Application filed June 16, 1919. Serial No. 304,523.

To all whom it may concern:

Be it known that I, NICHOLAS P. LEHR, a citizen of the United States, residing at Fremont, in the county of Sandusky and State of Ohio, have invented certain new and useful Improvements in Clod-Crushers and Packers; and I do declare the following to be a full, clear, and exact description of the invention, such as will enable others skilled in the art to which it appertains to make and use the same.

My invention relates to improvements in clod crushers and packers of the tandem type and the principal object is to provide for vertical movement of the front and rear rollers in passing over irregularities in the ground, without excessively jarring the driver as now commonly occurs, and without placing serious neck strain on the team.

A further object is to provide novel means for taking up any end play of the rollers, so that trailing of the circumferential ribs of the rear roller in the grooves made by the corresponding ribs of the front roller is impossible.

A still further object is to provide a machine which will be simple and inexpensive, yet highly efficient and in every way desirable.

With the foregoing objects in view, the invention resides in the novel construction and arrangement of parts hereinafter described and claimed, the descriptive matter being supplemented by the accompanying drawings.

Figure 1 is a perspective view of a machine constructed in accordance with my invention.

Fig. 2 is a vertical transverse section.

Figs. 3 and 4 are end elevations, partly broken away, showing the operation of the machine in passing over irregular surfaces.

I employ a frame 1 carrying the front and rear crushing and packing rollers 2 and 3, provide means for preventing end play of said rollers, slidably connect the rear end of the tongue 4 with said frame, and provide draft members 5 between said frame and tongue which will interfere in no manner with vertical oscillation of the frame nor with the consequent relative sliding of the tongue and frame. The driver's seat S is mounted on the tongue and since the frame and rollers may oscillate freely in passage over the earth, without similarly

moving said tongue, the driver is not continually jarred as by the tandem crushers now in use nor is excessive neck strain placed upon the team.

The features above briefly described may be embodied in numerous ways, but I prefer to employ the construction described specifically below.

The numerals 6 designate two cast metal end frames disposed vertically and connected by angle iron bars 7 which extend throughout the full width of the machine, said frames 6 and the bars 7 forming the present embodiment of the frame 1 above referred to. The frames 6 carry appropriate bearings 8 for the usual journals of the rollers 2 and 3, and in order that end play of said rollers may be prevented, I provide a transverse tie rod 9 connecting the lower ends of the frames 6 and having at least one nut 10. By tightening this nut, the lower ends of the frames 6 and the bearings 8 carried thereby, may be moved inwardly to compensate for any wear which may take place. The rollers 2 and 3 are provided with the usual circumferential ribs 11, and the ribs of the rear roller on the machines now in use, often trail in the grooves formed by the front ribs, when excessive wear has taken place and the two rollers are permitted to shift endwise. The implement is not therefore as effective as when the ribs of the rear roller operate upon the ridges left by the front rollers. It is therefore highly expedient to provide some means such as the rod 9 for preventing end play of the rollers.

The frame 1 carries one or more guides 12 in which a slide 13 on the rear end of the tongue 4 is movable. Two guides are preferably employed and I prefer to form them of slotted flanges depending from longitudinal bars 14 which are bolted or otherwise secured to the bars 7, and although the slide 13 could be of any adequate form, it is by preference in the form of a cross-head on the lower end of an arm 15 which depends rigidly from the rear end of the tongue 4, the ends of said cross-head sliding in the slots 16 of the flanges 12. These flanges will in most instances be provided with slots or other openings 17 through which the rod 9 passes, but if desired this rod could extend straight between the two frames 6, instead of being arched as shown.

The draft members 5 are preferably in

the form of two one-piece bars having their front ends pivoted to the tongue 4 at 18, while their rear ends are pivoted at 19 to the frames 6, in close proximity to the bearings of the front roller 2. Free oscillation of the frame of the machine is thus permitted without exerting neck strain upon the team, and at the same time an effective draft connection is at all times established 10 between the tongue and frame.

Since excellent results have been obtained from the details disclosed, they may well be followed, but within the scope of the invention as claimed, the machine may be embodied in numerous other forms, and changes in the form shown may be made.

I claim:

1. An implement of the class described comprising a frame, front and rear rollers 20 carried by said frame, a tongue extending forwardly from said frame, means establishing a sliding and pivotal connection between said frame and said tongue, and draft means between said tongue and frame extending upwardly from the sides of said frame to said tongue.

2. An implement of the class described comprising a frame, front and rear rollers carried by said frame, a longitudinal guide 30 carried by said frame, a tongue whose rear end is slideable along said guide and pivotal with respect thereto, and draft means between said tongue and frame, extending upwardly from the sides of the frame to 35 the tongue.

3. An implement of the class described comprising a frame, front and rear rollers carried by said frame, laterally spaced longitudinal guides on said frame, a tongue 40 having a depending arm received between said guides and provided with a cross head slideable along said guides and pivotal with

respect thereto, and draft means between said tongue and frame extending upwardly from the sides of the latter to said tongue.

4. An implement of the class described comprising a frame, front and rear rollers carried by said frame, parallel longitudinal bars secured to said frame and having depending flanges provided with longitudinal 50 slots, a tongue having on its rear end a depending arm received between said flanges, the lower end of said arm having a cross-head capable of sliding and turning in said slots, and draft means connecting said tongue and said frame.

5. An implement of the class described comprising rollers disposed in tandem, vertical side frames having bearings at their lower ends for said rollers, transverse bars 60 connecting the upper ends of said side frames, and a tie rod extending between the lower ends of said frames for drawing them inwardly toward each other to prevent end play of said rollers.

6. An implement of the class described comprising rollers disposed in tandem, vertical side frames having bearings at their lower ends for said rollers, transverse bars connecting the upper ends of said side 70 frames, and a tie rod extending between the lower ends of said frames for drawing them inwardly toward each other to prevent end play of said rollers; together with a longitudinal guide secured to said bars and having an opening through which said tie rod passes, a tongue whose rear end is slideable along said guide and pivotal with respect thereto, and draft means connecting said tongue and said side frames.

In testimony whereof I have hereunto set my hand.

NICHOLAS P. LEHP
